UNITED STATES PATENT OFFICE.

JOSEPH R. RIEHLE, OF BRONX, NEW YORK, ASSIGNOR TO OTTO R. GISCHOW, OF NEW YORK, N. Y.

DESIGN FOR A DIAL KNOB.

Application filed February 25, 1925. Serial No. 12,486. Term of patent 14 years.

To all whom it may concern:

Be it known that I, JOSEPH R. RIEHLE, a citizen of the United States, residing at Bronx, in the county of Bronx and State of New York, have invented a new, original, and ornamental Design for Dial Knob, of which the following is a specification, reference being had to the accompanying drawings, forming part hereof.

The design is shown in the accompanying drawings, in which—

Fig. 1 is a perspective view of the dial knob, and

Fig. 2 is a face view of the dial knob.

I claim:—

The ornamental design for a dial knob as shown.

JOSEPH R. RIEHLE.
